DOOR LATCH

George R. Feuerlein, Detroit, Mich., assignor to
 Roethel Engineering Corporation, Detroit,
 Mich., a corporation of Michigan

Application May 29, 1944, Serial No. 537,838

28 Claims. (Cl. 292—181)

1

This invention relates generally to door latches for various types of door structures. The invention is particularly, although not exclusively, useful in connection with latch devices adapted for use in connection with the doors of automobiles and other vehicles and contemplates the provision of an improved door latch including a preferably non-retractable latch bolt adapted to be installed upon a swinging door and an improved striker device cooperable with the bolt for shifting the same into latching position when the door is closed.

An object of the invention is to provide an improved device of the above class or type which is relatively simple and compact in construction, economical to manufacture, easily operated, durable and efficient in use, and which in operation is capable of providing an easy and relatively quiet closing door.

Another object of the invention is to provide an improved door latch embodying a latch bolt extending longitudinally at the free edge of the door and shiftable vertically both when closing and opening the door, means being provided for locking the bolt in a plurality of positions and additional means of a simple and efficient character being provided for releasing the bolt locking means to permit the door to be opened.

A further object of the invention is to provide an improved latch device in which a longitudinally extending non-retractable bolt is adapted to be shifted vertically, when closing the door, by engagement with an inclined striker or cam device and in which the bolt may be automatically locked in elevated position at one or more points on the inclined surface of the striker so as to hold the bolt positively against withdrawal.

Still another object of the invention is to provide an improved latch mechanism including a longitudinally extending bolt shiftable vertically, during closing of the door, by sliding engagement with an inclined surface, devices being provided for locking the bolt on said surface at a plurality of elevations and additional means controlled such as by a push button being provided for shifting said devices.

According to one aspect of the invention the bolt is carried by a vertically shiftable slide at all times urged downwardly toward unlatching position by a spring and the bolt locking devices being in the form of spring pressed swinging members urged at all times toward the slide so that each will automatically move into locking position when the bolt is at a predetermined elevation. According to a further aspect of the invention the

2

swinging bolt locking members are capable of being simultaneously swung out of locking position by a kick-out or releasing member adapted to be actuated to accomplish this purpose by means of a push button control.

Other objects of this invention will appear in the following description and appended claims, reference being had to the accompanying drawings forming a part of this specification wherein like reference characters designate corresponding parts in the several views.

Fig. 1 is a fragmentary horizontal section taken through a swinging door and adjacent pillar and illustrating an installation of a door latch constructed in accordance with the present invention.

Fig. 2 is a vertical section taken substantially through lines 2—2 of Fig. 1 looking in the direction of the arrows.

Fig. 3 is a vertical section taken substantially through lines 3—3 of Fig. 2 looking in the direction of the arrows.

Fig. 4 and Fig. 5 are views similar to Fig. 2 but illustrating different positions of the bolt and associated mechanism.

Fig. 6 is an enlarged fragmentary section taken substantially through lines 6—6 of Fig. 1 looking in the direction of the arrows.

Fig. 7 is an enlarged section taken substantially through lines 7—7 of Fig. 2 looking in the direction of the arrows.

Fig. 8 is a section taken substantially through lines 8—8 of Fig. 2 looking in the direction of the arrows.

Fig. 9 is a section taken substantially through lines 9—9 of Fig. 2 looking in the direction of the arrows.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the drawings there is illustrated, by way of example, one embodiment of the present invention as applied to a door structure, such as that of an automobile. The swinging door is hinged at one edge so as to swing against a common door post or body pillar in accordance with conventional practice and comprises an outer metal door panel 10 and an inner metal door panel 11. The

panel 11 terminates in a transverse jamb edge or portion 12 facing the fixed jamb face or edge 13 of the door post or body pillar 14.

The latch device proper comprises a case plate 15 engaging the inner surface of the inner door panel 11 and provided with a transversely extending flange 16 adapted to fit against the inner surface of the jamb edge 12 of the door. The case plate is rigidly secured in suitable manner, such as by screws, to the panel portions 11 and 12 of the door. Slidable vertically upon the inner face of the case plate flange 16 is a bolt carrying slide 17 to which is rigidly secured a bolt 18 projecting through a vertical slot 19 in the flange 16 and a corresponding vertical slot 20 (Fig. 6) in the jamb portion 12 of the door. Communicating slots 19 and 20 are preferably of the same height and are dimensioned so that the bolt 18 will have a sliding fit between the corresponding side edges thereof. The slide 17 is guided against the case plate flange 16 in a rectilinear vertical direction by means of guide studs 21 secured to the flange 16 and fitting within guide slots 21a in the slide 17. The slide 17 at its upper edge adjacent the case plate 15 is formed with an inturned flange or projection 22. At its lower edge the slide 17 is provided with an inturned flange or projection 23 the upper face of which is engaged at all times by one end of a spirally wound spring 24 anchored at its opposite end to the case plate. The spring is under tension at all times and exerts an effort on the slide 17 urging it downwardly into the position shown in Fig. 5.

For the purpose of locking the slide 17 in a plurality of elevated positions, such as the positions shown in Figs. 2 and 4, a pair of swinging locking members 25 and 26 are provided. These members are arranged face to face, as shown in Fig. 9, and are pivotally mounted at their lower ends upon a shoulder rivet 27 secured to the case plate. As shown more clearly in Fig. 4, the rear edge 25b of the locking member 25 is engaged by a spring 28 and the rear edge 26b of the locking member 26 is engaged by a similar spring 29. The springs 28 and 29 are arranged side by side and are anchored in common to a lug 30 struck out from the case plate. The locking members 25 and 26 are provided at their upper edges, as shown in Fig. 9, with outturned flanges 25a and 26a which are spaced apart a suitable distance vertically and are adapted to engage successively beneath the projection 22 on the slide 17 when the latter is shifted vertically predetermined distances. It will be readily seen that when the slide 17 is shifted vertically from the position shown in Fig. 5 to the position shown in Fig. 4, the locking member 25 will be forced by its spring 28 into position to bring the lug or flange 25a beneath the projection 22 on the slide thereby locking it in position. Continued upward movement of the slide to the position shown in Fig. 2 will result in the locking member 26 being forced by its spring 29 outwardly so as to force the flange or lug 26a thereof beneath the projection or lip 22 of the slide thereby locking the slide in the manner shown in Fig. 2. It will be seen that when the bolt 18 is in its lowermost position, as illustrated in Fig. 5, the locking members 25 and 26 will be held against outward movement under the influence of the springs 28 and 29 by the engagement of the edges 25c and 26c of these members with the edge of the projecting lug or lip 22 of the bolt slide. Likewise when the locking member 25 has been thrust for-

wardly to locking position beneath the projection 22, as shown in Fig. 4, the adjacent locking member 26 will be held against outward movement by its engagement with the edge of the projection or lip 22.

The locking members 25 and 26 may be retracted from their locking positions so as to release the bolt carrying slide 17 by means of a swinging lever or kick-out member 31, this member being positioned alongside of the locking member 25 and pivotally mounted at its lower end upon the stud or shoulder rivet 27. The lever 31 is provided with a laterally extending lug or flange portion 32 adapted to overlap and engage correspondingly shaped projecting portions 33 and 34 formed at the upper ends of the locking members 25 and 26. Thus, when the locking member 25 or when both locking members 25 and 26 lie beneath the projecting lip 22, as shown in either Fig. 4 or Fig. 2, the forward edge of the portion 33, as shown in Fig. 4, or the forward edges of both portions 33 and 34, as shown in Fig. 2, will abut against the flange or projection 32 on the lever 31. Hence, by retracting the lever, or swinging it to the right in Figs. 2 and 4, the locking members 25 and 26 will also be swung to the right thereby withdrawing the portions 25a and 26a from beneath the lip 22 on the bolt slide. When this occurs the bolt slide and bolt will be released and will be shifted downwardly to the position shown in Fig. 5 by the return spring 24. The lever 31 is guided in its swinging movement by means of a stud 35 secured to the case plate extending through and shiftable within an arcuate guide slot 36 in the lever. The lever 31 is normally urged outwardly toward the position shown in Figs. 2 and 4 by means of a spring 37. When, therefore, the lever is unrestrained it will normally assume the position shown in either Fig. 2 or Fig. 4 due to the action of the spring 37.

The upper edge of the lever 31 is provided with a notch or recess 38 to receive the flanged edge portion 39a of a locking slide 39 guided for vertical movement by means of guide slots 40 in the slide cooperable with guide studs 41 secured to the case plate. The locking slide may be shifted vertically in either direction through the medium of a plunger 42 provided with a knob 43 accessible at the inside of the door. By forcing the plunger downwardly the flange portion 39a of the locking slide will be positioned behind a flange portion 44 on the forward edge of the notch or recess 38, as illustrated in Fig. 2. With the parts in this position the lever 31 will be dogged against swinging movement, thereby preventing operation of the lever to shift the locking members 25 and 26 and release the bolt slide. As also illustrated in Fig. 2, the locking slide 39 may be shifted in either direction vertically through any conventional key operated lock 45 provided with an actuating member 46 controlled by turning the key in the lock and engaging in a notch 39b. Thus, the locking slide 39 may be shifted into and out of position behind the flange or abutment 44 either by shifting the plunger 42 or turning the key in the lock 45 to swing the member 46.

The present door latch is provided with means controlled by a push button mounted on the outside of the door for shifting the lever 31 rearwardly to withdraw the locking members 25 and 26 from beneath the locking lug or flange 22 on the bolt slide. The upper portion 31a of the lever 31 is provided with a flanged edge 31b normally projecting into position to be engaged by a bell crank lever 47 pivoted at 48 to a channel piece

49 notched or cut away to receive the lever 47, as illustrated in Fig. 8. The lever 47 has an arm 47b engaging the flanged edge 31b and also has a second arm 47a engaged by the inner end of a horizontal plunger 51 fitting within the channel piece 49 and guided therein by a pin and slot connection 52 and 53, see Figs. 3 and 8. Threaded into the outer end of the plunger 51 is the stem 54 of a push button 55. This button is confined within a recess 56 formed within an escutcheon or housing member 57 secured to the outer door panel 10, as shown in Fig. 1. By pressing the push button 55 inwardly within the recess 56 the plunger 51 will swing the lever 47 about its pivot 48 thereby swinging the kick-out lever 31 to the right in Fig. 2. This motion of the lever will be transmitted through the lug 32 to the locking members 25 and 26 thereby withdrawing them from beneath the locking lug or flange 22 on the bolt slide. It will be seen from Fig. 8 that the construction of the lever 47 is such as to translate inward sliding motion of the plunger 51 to the upper end 31a of the lever 31 into motion in a direction at right angles or transverse to the direction of movement of the plunger 51.

As particularly illustrated in Fig. 7, provision is made in the present latch structure for retracting the lever 31 to release the bolt slide through the medium of a push button control mounted on the inner door panel 11 at the inside of the vehicle. A bell crank lever 58 is pivoted at 59 to a channel bracket 60 secured to the case plate. This lever has an arm 58a projecting into a slot or aperture 61 in the lever 31 and engageable with one edge of the recess. The lever 58 is also provided with a second arm 58b engaged by a push button plunger 62 terminating in an annular button 62a housed and guided within a sleeve 63 anchored in a housing 65 secured to the inner door panel. Surrounding the push button 62 is a compression spring 64 normally urging the push button outwardly to the position shown in Fig. 7. By pushing the button inwardly the bell crank 58 will be swung on its pivot 59 thereby swinging the kick-out lever 31 to the right in Figs. 2 and 7 resulting in withdrawing the locking members 25 and 26 from beneath the locking flange or lug 22 on the bolt slide.

It will be understood that normally when the door is open the bolt 18 and its slide 17 will occupy their lowermost position, as illustrated in Fig. 5, through action of the spring 24. At this time the bolt 18 will lie at the lower end of the vertical slot 19 in the case plate flange 16 and also at the lower end of the slot 20 in the door jamb 12. The respective positions at this time of the bolt 18, slide 17 and locking members 25 and 26 are illustrated in Fig. 5. The bolt is moved upwardly within the guide slots 19 and 20 during closing movement of the door by means of a striker member 66 rigidly secured, as by means of screws, to the jamb edge 13 of the body pillar or post 14. This striker is provided with two projecting portions 67 and 68 spaced apart, as illustrated in Fig. 6, to provide an upwardly inclined guideway 69 through which the bolt 18 is adapted to travel in engagement with the spaced parallel faces of the striker portions 67 and 68.

As the door is closed the bolt 18 will enter the lower end of the guideway 69, as shown by the dotted line position of the bolt in Fig. 6, and thence will travel upwardly along the inclined face 68a of the striker portion 68. This face will operate to cam the bolt upwardly within the guide slots 19 and 20. It is preferred that

the width of the guideway 69 be such as to cause the lower inclined face 67a of the striker portion 67 to be in contact with the bolt as it travels upwardly within the guideway. The final locking position of the bolt within the inclined guideway is shown in full lines in Fig. 6, and when the bolt reaches this position the bolt carrying slide 17 will have reached the position shown in Fig. 2. During the upward travel of the bolt slide the locking member 25 will be forced beneath the locking flange 22 when the latter clears the flange 25a on the locking member. This member, therefore, provides a safety locking step by which the bolt slide will be locked against downward movement in case the bolt does not go fully home to the position shown in Fig. 6. When the bolt reaches this position, however, the second locking member 26 will be shifted beneath the bolt locking flange 22 thereby positively locking it in the fully closed position of the door. It is important, therefore, to note that the bolt 18 may be positively locked within the inclined guideway 69 in a plurality of vertical positions by means of the members 25 and 26 which, by preventing the bolt from being cammed downwardly and out of the guideway, positively prevent the door from opening except by swinging the kick-out lever 31 rearwardly to simultaneously withdraw the locking members 25 and 26 from beneath the locking flange or lip 22 on the bolt slide.

It will be noted that the upper surfaces of the flanges 25a and 26a as well as the bottom face of the flange 22 are correspondingly inclined or tapered. As a result of this construction the locking members will exert, under the influence of their springs, an upward wedging action against the flange 22 and assuring that the locking members will work their way fully home under the action of their springs. These inclined surfaces also facilitate withdrawal of the locking members when the push button 55 or the push button 62 is pressed to retract the lever 31. The upper surface 67b of the striker portion 67 is inclined for engagement by an inclined block 70 rigidly secured to the edge of the door immediately above the bolt 18. This block 70 in cooperation with the striker member 67 will assist in holding the door vertically against sagging and in cooperation with the latch bolt 18 will rigidly hold the door against movement in any vertical direction during operation of the vehicle.

It is further important to note that, due to the constant downward effort exerted by the return spring 24 on the bolt slide 17, as soon as the locking members are withdrawn from their locking positions the effort exerted by the spring on the bolt slide will be transmitted to the bolt tending to cam the bolt out of the guideway 69. This action will result in exerting an opening effort on the door. Thus, when the push button is pressed with the door in closed latched position the action of the spring will be to tend to force the bolt out of the striker guideway thereby tending to swing the door partially open. The extent of this opening effort on the door will depend on the strength of the spring 24 and the assistance from this spring desired in initiating the opening of the door. In the present latch an inside push button release, Fig. 7, is provided. However, any suitable remote control mechanism attached to the kick-out lever 31 may be provided where it is desired to retract this lever from a remote point of control. Further-

more, although two locking members for the safety and final locking steps are provided it will be understood that more than two locking members to provide additional locking steps may be employed.

I claim:

1. In a door latch, a case plate adapted to be mounted on a swinging door, a vertically movable slide on said plate, a longitudinally extending latch bolt secured to said slide and engageable with an inclined surface on a door frame member when the door is closed for shifting the slide upwardly, and a spring actuated locking member shiftable into position beneath a projecting portion on the slide when the latter reaches a predetermined elevation for positively locking the bolt slide against downward movement.

2. In a door latch, a case plate adapted to be mounted on a swinging door, a vertically movable slide on said plate, a longitudinally extending latch bolt secured to said slide and engageable with an inclined surface on a door frame member when the door is closed for shifting the slide upwardly, a spring actuated locking member shiftable into position beneath a projecting portion on the slide when the latter reaches a predetermined elevation for positively locking the bolt slide against downward movement, and means for withdrawing said locking member to release the slide.

3. In a door latch, a case plate adapted to be mounted on a swinging door, a vertically movable slide on said plate, a longitudinally extending latch bolt secured to said slide and engageable with an inclined surface on a door frame member when the door is closed for shifting the slide upwardly, a spring actuated locking member shiftable into position beneath a projecting portion on the slide when the latter reaches a predetermined elevation for positively locking the bolt slide against downward movement, and a swinging lever for withdrawing said locking member from beneath said projecting portion to release the slide.

4. In a door latch, a case plate adapted to be mounted on a swinging door, a vertically movable slide on said plate, spring means for urging said slide downwardly, a longitudinally extending latch bolt secured to said slide and engageable with an inclined surface on a door frame member when the door is closed for shifting the slide upwardly, and a spring actuated locking member shiftable into position beneath a projecting portion on the slide when the latter reaches a predetermined elevation for positively locking the bolt slide against downward movement.

5. In a door latch, a case plate adapted to be mounted on a swinging door, a vertically movable slide on said plate, spring means for urging said slide downwardly, a longitudinally extending latch bolt secured to said slide and engageable with an inclined surface on a door frame member when the door is closed for shifting the slide upwardly, a spring actuated locking member shiftable into position beneath a projecting portion on the slide when the latter reaches a predetermined elevation for positively locking the bolt slide against downward movement, and means for withdrawing said locking member to release the slide.

6. In a door latch, a case plate adapted to be mounted on a swinging door, a vertically movable slide on said plate, spring means for urging said slide downwardly, a longitudinally extending

latch bolt secured to said slide and engageable with an inclined surface on a door frame member when the door is closed for shifting the slide upwardly, a swinging spring actuated locking member shiftable into position beneath a projecting portion on the slide when the latter reaches a predetermined elevation for positively locking the bolt slide against downward movement, and a swinging lever for withdrawing said locking member from beneath said projecting portion to release the slide.

7. In a door latch, a supporting plate adapted to be mounted on a swinging door at one edge thereof, a vertically shiftable slide on said plate, a longitudinally extending latch bolt secured to the slide and projecting through aligned vertical slots in the plate and the edge of the door, said bolt being engageable with an inclined surface on a door frame member when the door is closed for shifting the bolt and slide upwardly, a plurality of swinging locking members having vertically spaced portions shiftable successively into positions beneath a projection on the slide for supporting the slide against downward movement, spring means for urging said locking members into said positions, and means for shifting said locking members out of position beneath said projection to release said slide.

8. In a door latch, a supporting plate adapted to be mounted on a swinging door at one edge thereof, a vertically shiftable slide on said plate, a longitudinally extending latch bolt secured to the slide and projecting through aligned vertical slots in the plate and the edge of the door, said bolt being engageable with an inclined surface on a door frame member when the door is closed for shifting the bolt and slide upwardly, a plurality of swinging locking members having vertically spaced portions shiftable successively into positions beneath a projection on the slide for supporting the slide against downward movement, spring means for urging said locking members into said positions, and push button controlled means for shifting said locking members out of position beneath said projection to release said slide.

9. In a door latch, a supporting plate adapted to be mounted on a swinging door at one edge thereof, a vertically shiftable slide on said plate, a longitudinally extending latch bolt secured to the slide and projecting through aligned vertical slots in the plate and the edge of the door, said bolt being engageable with an inclined surface on a door frame member when the door is closed for shifting the bolt and slide upwardly, a plurality of swinging locking members having vertically spaced portions shiftable successively into positions beneath a projection on the slide for supporting the slide against downward movement, spring means for urging said locking members into said positions, and swinging lever means for shifting said locking members out of position beneath said projection to release said slide.

10. In a door latch, a supporting plate adapted to be mounted on a swinging door at one edge thereof, a vertically shiftable slide on said plate, spring means for urging said slide downwardly, a longitudinally extending latch bolt secured to the slide and projecting through aligned vertical slots in the plate and the edge of the door, said bolt being engageable with an inclined surface on a door frame member when the door is closed for shifting the bolt and slide upwardly, a plurality of swinging locking members having vertically spaced portions shiftable successively into posi-

tions beneath a projection on the slide for supporting the slide against downward movement, spring means for urging said locking members into said positions, and means for shifting said locking members out of position beneath said projection to release said slide.

11. In a door latch, a supporting plate adapted to be mounted on a swinging door at one edge thereof, a vertically shiftable slide on said plate, a longitudinally extending latch bolt secured to the slide and projecting through aligned vertical slots in the plate and the edge of the door, said bolt being engageable with an inclined surface on a door frame member when the door is closed for shifting the bolt and slide upwardly, a plurality of swinging locking members having vertically spaced portions shiftable successively into positions beneath a projection on the slide for supporting the slide against downward movement, spring means for urging said locking members into said positions, and a swinging member for shifting one or both of said locking members out of supporting position beneath said projection to release said slide.

12. In a door latch, a supporting plate adapted to be mounted on a swinging door at one edge thereof, a vertically shiftable slide on said plate, spring means for urging said slide downwardly, a longitudinally extending latch bolt secured to the slide and projecting through aligned vertical slots in the plate and the edge of the door, said bolt being engageable with an inclined surface on a door frame member when the door is closed for shifting the bolt and slide upwardly, a plurality of swinging locking members having vertically spaced portions shiftable successively into positions beneath a projection on the slide for supporting the slide against downward movement, spring means for urging said locking members into said positions, and a swinging member for shifting one or both of said locking members out of supporting position beneath said projection to release said slide.

13. In a latch mechanism for a swinging door hinged at one edge to cause the opposite free edge to swing into and out of closed position with respect to an upright frame member, a vertically shiftable slide mounted on said free edge of the door, a latch bolt secured to the slide and extending through a vertical slot in said free edge of the door, spring means urging said slide downwardly, a striker on said frame member having an inclined surface adapted to cam the bolt upwardly in said slot when the door is closed to elevate said slide, means shiftable beneath a portion of the slide to support the same against downward movement and thereby lock the bolt on said inclined surface in an elevated position or positions of the slide, and means for retracting said first means to release the slide and permit it to move downwardly under the influence of its spring means thereby moving the bolt downwardly in said slot and along said inclined surface.

14. In a latch mechanism for a swinging door hinged at one edge to cause the opposite free edge to swing into and out of closed position with respect to an upright frame member, a vertically shiftable slide mounted on said free edge of the door, a latch bolt secured to the slide and extending through a vertical slot in said free edge of the door, spring means urging said slide downwardly, a striker on said frame member having an inclined surface adapted to cam the bolt upwardly in said slot when the door is

closed to elevate said slide, spring pressed means shiftable beneath a portion of the slide to support the same against downward movement and thereby lock the bolt on said inclined surface in an elevated position or positions of the slide, and spring pressed means for retracting said first means to release the slide and permit it to move downwardly under the influence of its spring means thereby moving the bolt downwardly in said slot and along said inclined surface.

15. In a latch mechanism for a swinging door hinged at one edge to cause the opposite free edge to swing into and out of closed position with respect to an upright frame member, a vertically shiftable slide mounted on said free edge of the door, a latch bolt secured to the slide and extending through a vertical slot in said free edge of the door, spring means urging said slide downwardly, a striker on said frame member having an inclined surface adapted to cam the bolt upwardly in said slot when the door is closed to elevate said slide, spring pressed means shiftable beneath a portion of the slide to support the same against downward movement and thereby lock the bolt on said inclined surface in an elevated position or positions of the slide, spring pressed means for retracting said first means to release the slide and permit it to move downwardly under the influence of its spring means thereby moving the bolt downwardly in said slot and along said inclined surface, and push button controlled means for shifting said retracting means in opposition to the spring pressure exerted thereon.

16. In a latch mechanism for a swinging door, a case plate, a vertically shiftable slide thereon, a projecting latch bolt fixed to the slide, a plurality of locking members pivoted at their lower ends with their upper ends swingable in one direction successively into positions beneath a projection on the slide to support the slide in successive vertically raised positions with the bolt thereby locked in corresponding vertically spaced positions, a releasing member shiftable in one direction to swing said locking members out of said positions beneath said projection to release the slide, spring means urging said releasing member in the opposite direction, and spring means urging the slide downwardly.

17. In a latch mechanism for a swinging door, a case plate, a vertically shiftable slide thereon, a projecting latch bolt fixed to the slide, a plurality of locking members pivoted at their lower ends with their upper ends swingable in one direction successively into positions beneath a projection on the slide to support the slide in successive vertically raised positions with the bolt thereby locked in corresponding vertically spaced positions, spring means urging said locking members into said positions, a releasing member shiftable in one direction to swing said locking members out of said positions beneath said projection to release the slide, spring means urging said releasing member in the opposite direction, and spring means urging the slide downwardly.

18. In a latch mechanism for a swinging door, a case plate, a vertically shiftable slide thereon, a projecting latch bolt fixed to the slide, a plurality of locking members pivoted at their lower ends with their upper ends swingable in one direction successively into positions beneath a projection on the slide to support the slide in successive vertically raised positions with the

bolt thereby locked in corresponding vertically spaced positions, a releasing member shiftable in one direction to swing said locking members out of said positions beneath said projection to release the slide, spring means urging said releasing member in the opposite direction, spring means urging the slide downwardly, and push button controlled mechanism for shifting said releasing member to release the slide.

19. In a latch mechanism for a swinging door, a vertically shiftable slide, a projecting latch bolt fixed to the slide, a plurality of locking members, spring means for shifting said locking members successively beneath a projection on the slide when the slide is shifted upwardly thereby to lock the slide in successive vertically raised positions, spring means for urging the slide downwardly, said locking members engaging said slide under spring pressure when the slide is in its down position, a shiftable kick-out member positioned for engagement with said locking members when in their locking positions beneath said projection, spring means urging said kick-out member to said engaging position, a plunger shiftable transversely to the direction of movement of the kick-out member, means responsive to movement of the plunger for shifting the kick-out member to withdraw said locking members from beneath said projection, and a push button for actuating said plunger.

20. In a latch mechanism for a swinging door, a vertically shiftable slide, a projecting latch bolt fixed to the slide, a plurality of locking members, spring means for shifting said locking members successively beneath a projection on the slide when the slide is shifted upwardly thereby to lock the slide in successive vertically raised positions, spring means for urging the slide downwardly, said locking members engaging said slide under spring pressure when the slide is in its down position, a shiftable kick-out member positioned for engagement with said locking members when in their locking positions beneath said projection, spring means urging said kick-out member to said engaging position, a plunger shiftable transversely to the direction of movement of the kick-out member, means responsive to movement of the plunger for shifting the kick-out member to withdraw said locking members from beneath said projection, a push button for actuating said plunger, and a striker device having an upwardly inclined passage to slidably receive said bolt and adapted to cam the bolt upwardly as the door is closed thereby to shift said slide upwardly.

21. In a door latch, a support adapted to be mounted on a swinging door, a slide movable up and down on said support, a longitudinally extending latch bolt secured to said slide and engageable with an inclined surface on a door frame member when the door is closed for shifting the slide in one generally vertical direction, said slide having a projecting portion, and a spring actuated locking member shiftable into a position in which said projecting portion and locking member are in overlapping relation when the slide reaches a predetermined position for positively blocking vertical movement of the slide in the opposite direction.

22. In a door latch, a support adapted to be mounted on a swinging door, a slide movable up and down on said support, a longitudinally extending latch bolt secured to said slide and engageable with an inclined surface on a door frame member when the door is closed for shifting the

slide in one generally vertical direction, said slide having a projecting portion, a spring actuated locking member shiftable into a position in which said projecting portion and locking member are in overlapping relation when the slide reaches a predetermined position for positively blocking vertical movement of the slide in the opposite direction, and means for withdrawing said locking member to release the slide.

23. In a door latch, a support adapted to be mounted on a swinging door, a slide movable up and down on said support, a longitudinally extending latch bolt secured to said slide and engageable with an inclined surface on a door frame member when the door is closed for shifting the slide in one generally vertical direction, said slide having a projecting portion, a spring actuated locking member shiftable into a position in which said projecting portion and locking member are in overlapping relation when the slide reaches a predetermined position for positively blocking vertical movement of the slide in the opposite direction, and spring means for imparting return vertical movement to the slide in said last named direction.

24. In a door latch, a support adapted to be mounted on a swinging door at one edge thereof, a vertically shiftable slide on said support, a longitudinally extending latch bolt secured to the slide and projecting through aligned vertical slots in the support and the edge of the door, said bolt being engageable with an inclined surface on a door frame member when the door is closed for shifting the bolt and slide in one vertical direction, a plurality of swinging locking members having vertically spaced portions shiftable successively into positions with respect to a projection on the slide for blocking return vertical movement of the slide in the opposite direction, spring means for urging said locking members into said positions, and means for shifting said locking members out of blocking relation to said projection to release said slide.

25. In a door latch, a support adapted to be mounted on a swinging door at one edge thereof, a vertically shiftable slide on said support, a longitudinally extending latch bolt secured to the slide and projecting through aligned vertical slots in the support and the edge of the door, said bolt being engageable with an inclined surface on a door frame member when the door is closed for shifting the bolt and slide in one vertical direction, a plurality of swinging locking members having vertically spaced portions shiftable successively into positions with respect to a projection on the slide for blocking return vertical movement of the slide in the opposite direction, spring means for urging said locking members into said positions, means for shifting said locking members out of blocking relation to said projection to release said slide, and spring means for imparting return vertical movement to the slide.

26. In a latch mechanism for a swinging door hinged at one edge to cause the opposite free edge to swing into and out of closed position with respect to an upright frame member, a vertically shiftable slide mounted on said free edge of the door, a latch bolt secured to the slide and extending through a vertical slot in said free edge of the door, spring means urging said slide in one vertical direction, a striker on said frame member having an inclined surface adapted to cam the bolt in the opposite vertical direction in said slot when the door is closed, means shiftable into engagement with a portion of the slide

to block the same against movement in said first named direction and thereby lock the bolt on said inclined surface in a vertically moved position or positions of the slide, and means for retracting said last means to release the slide and permit it to move vertically under the influence of its spring means thereby moving the bolt vertically in said slot and along said inclined surface.

27. In a latch mechanism for a swinging door, a support, a vertically shiftable slide thereon, a projecting latch bolt fixed to the slide, a plurality of locking members pivoted adjacent certain ends thereof with their opposite ends swingable in one direction successively into positions to engage a projection on the slide to hold the slide in successive vertically shifted positions with the bolt thereby locked in corresponding vertically spaced positions, a releasing member shiftable in one direction to swing said locking members out of said positions with respect to said projections so as to release the slide, spring means urging said releasing member in the opposite direction, and spring means urging the slide toward unlocking position of the bolt.

28. In a latch mechanism for a swinging door, a vertically shiftable slide, a projecting latch bolt fixed to the slide, a plurality of locking members, spring means for shifting said locking members successively into engagement with a projection on the slide when the slide is shifted in one vertical direction thereby to lock the slide in successive vertically shifted positions, spring means for urging the slide in the opposite direction, said locking members engaging said slide under spring pressure when the slide is in normal bolt unlocking position, a shiftable kick-out member positioned for engagement with said locking members when in their locking positions with respect to said projection, spring means urging said kick-out member to said engaging position, a plunger shiftable transversely to the direction of movement of the kick-out member, means responsive to movement of the plunger for shifting the kick-out member to withdraw said locking members from said projection, and a push button for actuating said plunger.

GEORGE R. FEUERLEIN.
